Patented June 28, 1921.

UNITED STATES PATENT OFFICE.

JOHN W. DORSEY, OF WINNIPEG, MANITOBA, CANADA.

PARTY-LINE LOCKOUT FOR TELEPHONE SYSTEMS.

1,382,766.

Specification of Letters Patent. Patented June 28, 1921.

Application filed June 20, 1917. Serial No. 175,798.

To all whom it may concern:

Be it known that I, JOHN W. DORSEY, a citizen of the United States, residing at Winnipeg, in the Province of Manitoba, in 5 the Dominion of Canada, have invented new and useful Improvements in Party-Line Lockouts for Telephone Systems, of which the following is a specification.

My invention relates to telephone systems 10 and has for its object the provision of a simple party-line lockout and signaling device for use in common battery substation circuits.

Stated in general terms, I attain my object by providing a test relay bridged across the line by the subscriber in initiating a call, this relay becoming energized if the line is idle, to connect the talking set in parallel with itself across the line. The relay armature is provided with a signaling means, whereby the calling subscriber is audibly informed if the line is clear; and a key and supplemental signaling device are also provided whereby a subscriber already 25 on the line may call another subscriber on the same line. In a typical circuit, the ringer, the test relay, the talking set, and the auxiliary signaling device are in parallel bridges, the last three controlled by 30 the switch-hook and the special signaling key; and the circuit is so designed that in applying it to a desk set, not more than three conductors need be used in the cord.

My invention is illustrated in the accompanying drawings in which—

Figure 1 is a diagrammatic view of a substation equipped with my improved lockout system.

Fig. 2 is a modified arrangement of the apparatus using the same circuit arrangement.

Fig. 3 is a diagram of the invention applied to a system using selective ringing.

Fig. 4 is a diagram showing my invention 45 applied to the Kellogg substation circuit.

Fig. 5 is a diagram showing the theoretical circuit arrangement, the different bridges being indicated by legends thereon.

Referring to the drawings in detail and 50 first to Figs. 1 to 3, these show the invention applied in different ways to the Western Electric type of substation circuit. In Fig. 1 the line wires 1 and 2 of a common battery exchange system extend to a plurality of branch station lines as indicated

at 3—4 and 5—6. As in this system the apparatus and circuit arrangement at each station is the same, only one will be here shown and described. The substation apparatus consists of the usual switch-hook H, receiver R, transmitter T, induction coil I, talking and ringing condensers C and C', and a ringer Q of any type responsive to a fluctuating or interrupted current, and in addition to these usual apparatus elements, 60 I provide a combination signal and cut-in relay S, vibrator V, and control key K. The relay S is a potential relay wound, preferably, to about 3,000 ohms or of such resistance as to make the drop across the line 70 substantially negligible when connected thereacross, its required resistance therefore depending upon the voltage of the system in which it is used, the present arrangement being for a system using about 20 volts at 75 the exchange. The relay S is provided with a vibratory spring armature 7 normally disengaged from the contact 8, the parts being so arranged that the armature 7 will continue to vibrate for an appreciable time 80 after it has been thrown into engagement with the contact 8 upon the energization of the relay.

The circuit connections are as follows: 85 The ringer Q is normally connected across the line in series with the condenser C' through the branch line 3—4. The relay S is arranged to be connected in bridge of the line through the switch-hook contact 9 upon raising of the switch-hook H. This connection may be traced as follows: Line wire 1, branch wire 3, relay S, conductor 10, binding post 11, cord conductor 12, binding post 13, switch-hook contact 9, switch-hook H, binding post 14, cord conductor 15, binding 90 post 16, and conductor 4 back to line wire 2. The normally closed contact 17 of the key K and the normally open relay contact 8 control the connection of the transmitter T across the line in series with one winding 100 of the induction coil I. The connection may be traced from line wire 1, branch 3, armature 7, contact 8, contact 17, induction coil I, conductor 18, conductor 19, transmitter T, contacts of switch-hook, binding post 14, cord conductor 15, binding post 16, branch conductor 4, and back over line wire 2. The normally open contact 19 of the key K is connected to control the connection of the vibrator V in bridge of the line and in 110

series with the contact 8 of the relay S, which circuit may be traced from line wire 1, over branch conductor 3, armature 7, contact 8, contact 19, vibrator V, and back 5 through branch line 4 to the other side of the main line 2.

The operation is as follows: The subscriber on the branch line 3—4, desiring a connection with the substation on the branch 10 line 5—6, raises his receiver from the hook which connects the relay S in bridge of the main line over the circuit previously traced. If at this moment the line is idle, the voltage across the line conductors 1—2 will be sufficiently high to energize the potential relay S which upon energization attracts its armature 7 into engagement with the contact 8, the armature continuing to vibrate for an appreciable length of time. The engagement 15 of the armature 7 with the contact 8 completes the calling subscriber's battery supply circuit which is the same as that previously described for the connection of the transmitter T in bridge of the line, and the armature 7 continuing to vibrate, sets up fluctuations in the supply circuit in unison with its vibrations, giving the subscriber a signal through his receiver which indicates to him that the line is idle. This connection 20 of the transmitter circuit across the line causes a substantial drop in voltage which in practice, with a system of 20 volts, brings the potential across the line down to about one volt, which, however, is amply sufficient 25 to hold the relay S energized, its armature having already been attracted and the air gap reduced to a minimum. The closure of the line circuit signals the operator at the central station in the usual manner and 30 through the usual line terminal apparatus, and the operator connecting in on the line in response to this signal causes an increase in the line potential which in practice is found to come to about 6 volts. The subscriber on 35 the branch line 3—4 now signals the desired substation by actuating the key K to close the contact 19 and open the contact 17. The opening of the contact 17 disconnects the heavy circuit of the transmitter from the 40 line and connects the vibrator V in bridge of the line over the circuit previously described. As the transmitter circuit is now removed from the line, the voltage thereacross is influenced only by the drop across 45 the terminals of the relay S and the vibrator V, the drop due to the connection of the relay S being negligible, while the vibrator V is so wound as to bring the line voltage down to the minimum required to hold the 50 relay S energized, which in practice is found to be about one volt. Each time the vibrator opens its circuit, the line is opened except for the relay S so that the actuation of the vibrator produces a fluctuation of the line 55 potential which in practice is found to be

from about 1 to 20 volts. The ringers Q and condensers C' of all the branch circuits respond to these fluctuations, the particular subscriber desired being selected by means of the usual code signal which the calling 70 subscriber is enabled to give by suitable operation of the calling key K. The party on branch line 5—6, responding to the call, raises his receiver from the switch-hook which closes his switch-hook contacts and 75 connects his transmitter circuit across the line in a manner similar in all respects to that described for the calling subscriber, and which brings them into multiple connection with the main line 1—2 for conversation 80 thereover, both parties being supplied with current from the common battery central station.

Should the main line be busy, due to the connection of one of the substations therewith, when a second or third party attempts to connect with the line by raising his receiver from the switch-hook, the high-resistance relay S will become connected across the line but will not become energized to 90 attract its armature due to the substantial drop in voltage caused by the connection of the heavy transmitter circuits or circuit of the other branch lines or line across the main line. Thus a second or third party coming onto the line after another party has raised his receiver to make a call or after two other parties have become connected for conversation, will not receive the idle signal and so 95 will be aware that the line is already in use. 100 It is to be pointed out here, however, that when the second party raises his receiver in response to a call from a party previously connected to the line and at the moment operating his vibrator V, the relay S of the answering subscriber will become energized during one of the interruption periods of the calling party's vibrator at which moment the fluctuating voltage on the line is at its maximum.

While I have here shown the combination cut-in and signaling relay S in simple diagrammatic form, it is to be understood that the vibratory armature 7, its base 23 and tuning weight 22, and the contact 8, may be variously formed and arranged to meet the requirements of practice and all such variations of form and arrangement as fall within the scope of the appended claims are contemplated by me.

In the apparatus arrangement of Fig. 1, I have shown all the apparatus to the right of the dotted line as mounted in the usual wall box with four conductors 20, 21, 12 and 15 leading therefrom to the usual desk set indicated to the left of the dotted line and consisting of the switch-hook, transmitter and receiver, the conductors 20, 21, 12 and 15 representing the usual flexible cord or cable. In the arrangement of Fig. 2, the apparatus 130

shown to the right of the dotted line is mounted in the wall box while that shown to the left is carried by the desk set. With this arrangement only three conductors are required in the flexible cable between the wall box and desk set. The difference between Figs. 1 and 2 lies only in the positioning of the apparatus elements, the circuit arrangement being identically the same.

10 The arrangement shown in Fig. 3 is the same as that of Fig. 2 with the exception that the vibrator V and signal control key K are omitted and the signaling effected by means of any suitable selective ringing system controlled from the central office.

15 In Fig. 4, the invention is shown applied to the Kellogg substation circuit. Here the arrangement excluding the talking circuit, is the same as that of Fig. 2, that is, the 20 relay S is connected in bridge of the line and in series with the normally open switch-hook contact, the vibrator V is connected in bridge of the line and in series with the normally open contact 19 of the key K and the 25 contact 8 of the relay S, and the battery supply or transmitter circuit is connected across the line in series with the normally open switch-hook contact, key contact 17 and relay contact 8.

30 From the foregoing it will be seen that I have provided an effective lockout and signal system with the addition only of a simple relay, key and vibrator to an existing type of substation circuit, and an effective lockout system with the use only of a novel and simple form of relay in addition to an existing type of substation circuit and selective ringing system for example as the embodiment shown in Fig. 3.

40 Having thus described my invention what I claim and desire to secure by Letters Patent is—

1. In a common battery telephone exchange system a combined party line lockout and signaling system for installation at the substation only, comprising a potential relay controlling the talking circuit of its associated substation and arranged to be connected in bridge of the line upon raising 45 of the switch-hook, means energized from the central station for effecting a rapid fluctuation of the potential across the line above such minimum as will hold said potential relay energized, said potential varying means being arranged to be operable only during the energization of said relay, signal controlling means operable by the subscriber to open the talking circuit and render said potential varying means operable, and signaling means responsive to said 50 potential fluctuations.

2. A party line lockout system comprising, at each substation, a potential relay normally holding the talking circuit open and 55 responsive to the closing of the switch-hook

contacts to close the talking circuit and produce current fluctuations therein for an appreciable time.

3. A combined partly line lockout and signaling system for installation at the substation only, comprising a potential relay controlling the talking circuit of its associated substation and arranged to be connected in bridge of the line upon raising of the switch-hook, means for effecting a rapid 75 fluctuation of the potential across the line above the minimum required to hold said potential relay energized, said potential varying means being arranged to be operable only during the energization of said relay, signal 80 controlling means operable by the subscriber to open the talking circuit and render said potential varying means operable, and signaling means responsive to said potential fluctuations, said relay being arranged to produce current variation in the talking 85 circuit during an appreciable time after the closure thereof.

4. In a party-line telephone system, a line circuit, a source of current therefor, a talking set, a test relay controlling the connection of the talking set with the line and responsive to current in the line when the line is clear, only, a switch hook controlling the connection of the relay to the line, and 90 means actuated by said relay in its operation to produce current fluctuations in the talking circuit for an appreciable length of time, whereby the calling subscriber is apprised of the line condition by a sound or 95 by silence, as the case may be.

5. In a party-line telephone system, a line circuit, a source of current therefor, a talking set, a test relay controlling the connection of the talking set with the line and responsive to maximum potential only due to said source, a switch hook controlling the connection of the relay to the line, and means actuated by said relay in its operation to produce current fluctuations in the 105 talking circuit for an appreciable length of time, whereby the calling subscriber is apprised of the line condition by a sound or 110 by silence, as the case may be.

6. In a central energy party-line telephone system, a line circuit, and a plurality of bridged stations on the line, a signal receiving device such as a polarized ringer, a talking bridge and a high resistance test relay bridge at each station, a switch hook 115 controlling the relay bridge, the relay controlling the talking bridge, a vibrator bridged direct across the line, and a key with normally closed contacts in the talking bridge and normally open contacts in 120 said vibrator bridge.

7. A party line lockout substation equipment comprising a talking set, a ringer-condenser and a test relay, a talking circuit controlled by said relay, a switch hook on 130

said talking set controlling the circuit of said relay, and a flexible cord which contains not more than three wires connecting said talking set with said ringer-condenser and relay.

8. In a telephone system employing a common source of direct current at the central station, a party-line circuit, signaling means at each subscriber's station on the 10 party-line comprising a polarized receiving device normally responsive to alternating current, a condenser in series therewith, a vibrator at each subscriber's station arranged to be energized from a central station, and operable over the line to charge and discharge said condenser through said ringing means.

9. In a central energy telephone exchange system, a party-line, a plurality of sub-stations on said line, each sub-station having a polarized ringer and a condenser connected in series across the line, a high resistance relay bridged across the line and controlling the talking circuit, and means 25 energized by direct current from the central station operable to rapidly connect and dis-

connect a low resistance in bridge of the line, whereby a fluctuation of potential on the line above the minimum required to hold said high resistance relay energized is effected with the result that the condenser is charged and discharged in series with the ringer.

10. A party line lockout sub-station circuit for centralized energy telephone exchange systems, comprising an induction coil, receiver, transmitter and switch hook, the primary winding of said induction coil and the transmitter being connected in series, the secondary winding of the induction 40 coil, the receiver and a condenser being connected in series with each other and in shunt across the transmitter, a single pair of contacts controlled by said switch hook connected in series with the transmitter circuit across the line, and a high resistance relay also connected in series with said switch hook contacts across the line in shunt of said transmitter circuit.

In testimony whereof I have hereunto set 50 my hand.

JOHN W. DORSEY.
